A. Ely Beach.

United States Patent Office.

A. ELY BEACH, OF STRATFORD, CONNECTICUT.

Letters Patent No. 91,071, dated June 8, 1869.

IMPROVED SHIELD FOR TUNNELLING.

The Schedule referred to in these Letters Patent and making part of the same.

To all whom it may concern:

Be it known that I, A. ELY BEACH, of Stratford, in the county of Fairfield, and State of Connecticut, have invented a new and improved Shield for Excavating and Tunnelling; and I do hereby declare that the following is a full, clear, and exact description thereof, which will enable others skilled in the art to make and use the same, reference being had to the accompanying drawings, forming part of this specification.

Figure 1 is a perspective view of my improvement, showing its use in connection with the building of an underground tunnel.

Figure 2 is a side sectional view of the same.

Figure 3, an elevation of the rear end of the shield.

Figure 4, a sectional elevation of a portion of the shield and one of the binding-rods.

Figure 5, a sectional elevation of a portion of the shield and one of the pushing-devices by which the shield is moved.

Similar letters of reference indicate corresponding parts.

The shield consists of a cylinder, A, within which the workmen are protected while they excavate the earth in front of the shield. The latter is advanced as fast as the earth is excavated, by means of any suitable pushing-device, such as hydraulic jacks, or screws B, arranged to operate between the shield and the tunnel, the latter being constructed as fast as the shield is pushed forward.

The shield A may be composed of wood, metal, or other suitable material, of one or more pieces, and may be of a cylindrical or other desired form. In the present example, I compose the body of the shield of strong wooden staves a, tongued and grooved together, and I arm the front edge of the cylinder with a bevelled shoe of iron, b, made with a recess in its back edge, to receive the front ends of the staves, which are tongued therein as shown.

The rear edges of the staves are tongued and fitted into a recess in the face of a protecting-ring, c, of iron. The staves a are clamped between the ring and shoe, by means of strong longitudinal screw-bolts d, which extend from the shoe b through the staves to ring c, where the bolts are tightened by means of nuts. (See fig. 4.)

The pushing-devices, which in the present example consist of screws B, are arranged at suitable distances apart upon the ring c, through which they pass into recesses in the staves, nuts or female screws being located in or upon the ring.

The pushing-devices B can be thus withdrawn into the shield, by which they are supported ready for use, but out of the way until wanted.

Instead of working the screws singly, they may be all worked simultaneously, by means of a suitably-arranged wheel, operated by power.

When desired, the pushing-devices may consist of

hydraulic jacks, which may occupy the places upon the shield of the screws, and the said jacks, like the screws, may be arranged to withdraw into the shield.

Each jack may have an independent pump and liquid-reservoir, so as to be worked independently, or, if preferable, all the jacks may be connected by separate pipes, or by a common pipe with a single pump and reservoir, in such a manner that all the jacks may be operated simultaneously by one pump.

A stop-valve is to be so arranged, in connection with each of the jacks, that any one of them can be shut off at the will of the operator, from the pump.

The pressure to direct and drive the shield can thus be conveniently regulated.

More than one pump may be employed if desired, and the pump or pumps may be arranged upon the shield, or, if preferred, away from the shield, with suitable conducting-pipes extending to the jacks.

The pushing-devices are to be so arranged or attached to the shield that they will be carried upon and supported by it.

The rear end of the shield A is provided with a thin hood, C, preferably of sheet-steel, the object of which is to prevent the caving of the earth at the rear of the shield when the latter is advanced while the tunnel is being constructed.

In operating the shield, the rear part of the hood C is intended to rest upon the exterior of the tunnel, which is built up within the hood. The latter is made in sections, the ends of which are riveted together, and the hood is secured to the shield by means of bolts, which pass through the staves to the interior of the shield.

In case it becomes necessary to remove the hood, or any section thereof, it will be only necessary to drive out the bolts which fasten the hood to the shield, and cut the section-rivets.

The shield itself can readily be taken apart by unscrewing the nuts of the screw-bolts d, when the shoe, ring, and staves may be readily separated.

In soils where an additional protection against caving is required, I provide the front part of the shield with a series of sliding staves, D, so constructed and arranged that they may be driven forward from within the tube into the soil.

In the present example, the sliding staves D are made with double arms, forked in form, one arm resting on the exterior of the shield, the other arm fitting upon the interior, the inner arm being slotted and guided by stops e e, as shown.

The front ends of the staves D are bevelled, so as to present a cutting-edge to the soil. They may also be pointed.

The sliding staves are intended to be arranged side by side, and to encircle the front portion of the shield; but they may be made of any suitable length, and any suitable number of them may be employed.

The use of the sliding staves will be found especially

advantageous when stones are encountered, as the staves may be pushed forward, by the application of force to their inner arms, and they may thus be driven and fitted against the inequalities of the stone, so as to afford protection to the workmen while cutting or drilling the stone from the interior of the shield.

I do not confine myself to the use of sliding staves, of the particular form herein shown; nor do I limit myself to the form of any of the parts herein described, as they may be severally altered in many ways without departing from my invention.

What I claim as new, and desire to secure by Letters Patent, is—

1. The shield A, made and operating substantially as herein shown and described.
2. The arrangement of the pushing-devices to withdraw into the shield, as herein shown and described.

3. Arming the front of the shield with a cutting-shoe, substantially as herein shown and described.

4. The combination of the ring, shoe, and staves, substantially as shown and described.

5. The hood C, employed substantially as shown and described.

6. Providing the shield with sliding staves, substantially as and for the purposes herein shown and described.

7. The arrangement of the pushing-devices, so that they will be carried by and supported upon the shield, substantially as and for the purposes herein described.

A. ELY BEACH.
